[21] Appl. No.: 277,218

CLAIM

The ornamental design for a traveler's jacket, as shown and described.

DESCRIPTION

FIG. 1 is a front perspective view of a traveler's jacket showing my new design;

FIG. 2 is a rear elevational view thereof;

FIG. 3 is an enlarged fragmentary perspective view of an open pocket for clarity of illustration; and

FIG. 4 is an enlarged fragmentary perspective view of a closed pocket, again for clarity of illustration.
